ATTORNEY

UNITED STATES PATENT OFFICE.

RALPH PETTI, OF BRIDGEPORT, CONNECTICUT, ASSIGNOR TO THE SINGER MANUFACTURING COMPANY, A CORPORATION OF NEW JERSEY.

SEWING-MACHINE LOOP-TAKER.

1,351,869.

Specification of Letters Patent. Patented Sept. 7, 1920.

Application filed April 24, 1918. Serial No. 230,407.

To all whom it may concern:

Be it known that I, RALPH PETTI, a citizen of the United States, residing at Bridgeport, in the county of Fairfield and State of Connecticut, have invented certain new and useful Improvements in Sewing-Machine Loop-Takers, of which the following is a specification, reference being had therein to the accompanying drawings.

This invention relates to improvements in sewing machine loop-takers and more particularly to loop-takers adapted to cast needle-thread loops around a thread-case having a limited movement upon its own axis.

The invention has for its primary object to simplify and improve the constructions heretofore employed to effect an unobstructed passage for the needle-thread loop in its travel around the thread-case, in so far as said needle-thread would meet with interference or resistance by the means used for limiting the rotation of said case.

In the present construction, the thread-case is as usual provided with a stop-lug adapted to enter a notch formed in a lug on the under side of the throat-plate and is further provided with a circumferential rib seated in an annular raceway in the body of the loop-taker. The thread-case is bodily moved laterally by positioning the annular raceway eccentrically to the axis of the loop-taker. The consequent motion of the thread-case is controlled by means of a cam-element projecting therefrom and intermittently in sliding contact with a cam-surface on a stationary cam-lug projecting from the throat-plate. The resulting action is such that the needle-thread loop obtains a free passage past the opposite sides of the stop-lug and also past the controlling cam-surfaces.

In the accompanying drawings, Figure 1 is a sectional front side elevation of a sewing machine embodying the present improvement. Fig. 2 is a plan view of the throat-plate and the loop-taker and shows the stop-lug in the position it attains for the passage of one limb of the needle thread loop immediately after the taking of the loop by the loop-taker. Fig. 3 is a view similar to Fig. 2 but with the stop-lug contacting with the opposite side of its coacting notch to provide a passage for the limb of the loop and permit drawing up of the loop preliminary to setting the stitch. Fig. 4 is a top-plan

view of the loop-taker with the thread-case removed and with the raceway cover partly swung out of position to better show the eccentric raceway. Fig. 5 is a sectional view on the line A—A, of Fig. 3. Fig. 6 is a 60 sectional view of the throat-plate and co-acting stop-elements.

Referring to the drawings, the sewing machine is as usual constructed with a base 1 supporting the overhanging bracket-arm 2 terminating in the head 3. Journaled in bearings provided in the arm 2 is the main or driving shaft 4 adapted, in the usual manner, to actuate the needle-bar 5, journaled for vertical reciprocation in suitable 70 bearings provided in the head 3 and carrying the needle 6. The shaft 4 has driving connections with a shaft 7, journaled in bearings provided in the base 1 and adapted in a well known manner to impart to the 75 vertical loop-taker shaft 8 a plurality of rotations to one of the main-shaft. Carried by the loop-taker shaft 8 is the body 9 of the loop-taker having a loop-seizing beak 10. The cylindrical thread-case 11 is provided 80 with a peripheral bearing rib 12 seated in an annular raceway 13 formed in the body of the loop-taker eccentrically to the axis thereof. In order to permit insertion and removal of the thread-case, a cover 14 forming a portion of the upper wall of the raceway is secured by means of screws, as 15, to the loop-taker.

Rotation of the thread-case 11 upon its own axis is limited by the provision thereon 90 of a cam-element in the form of a stop-lug 16 adapted to contact with either of the walls 17 and 18 of a stop element in the form of a notch provided in a lug 19 projecting from the under side of the throat- 95 plate 20. The thread-case 11 is further provided with a cam-element 21 adapted to intermittently contact with a cam-surface 22 formed on a lug 23 projecting from the throat-plate.

In operation, the loop-taker beak 10 seizes the loop of thread presented by the needle 6 and casts it around the thread-case 11 in the usual manner. The normal tendency of the stop-lug 16 owing to the frictional contact between the thread-case and the loop-taker is to contact with the wall 18 on the lug 19. After the seizing of the loop by the loop-taker, it is necessary for the limb of the loop cast around the outer 110

face of the thread-case to pass between the stop-lug 16 and the wall 18. In order to facilitate its passage the eccentric raceway at this time carries the thread-case laterally to cause the cam-element 21 to contact with the cam-surface 22 and slightly oscillate the thread-case oppositely to the direction of rotation of the loop-taker. This position is illustrated in Fig. 2 of the drawings. As 10 the loop is drawn up by the usual take-up 24 it is necessary for it to pass between the cam-element 21 and the cam-surface 22, and also between the stop-lug 16 and the wall 17. Before the limb of the loop reaches the 15 cam-element 21, the eccentric raceway carries the thread-case laterally to open a passage for the loop, the thread-case at this time following its normal tendency to rotate with the loop-taker until the stop-lug 20 contacts with the wall 18. This position is illustrated in Fig. 3 of the drawings.

The present improvement therefore provides simple and effective means obviating the necessity of the needle-thread loop to 25 at any time force a passageway past either side of the stop-element usually employed for limiting rotation of the thread-case upon its own axis.

Having thus set forth the nature of the 30 invention, what I claim herein is—

1. In a sewing machine, a stitch-forming mechanism including a reciprocating needle, a loop-taker, a thread-case mounted in said loop-taker and around which said loop-taker is adapted to cast a loop of needle-thread, a stop-element for limiting rotation of said thread-case upon its own axis, and means for moving said thread-case axis laterally to provide a free passage for the needle-thread loop past said stop-element.

2. In a sewing machine, a stitch-forming mechanism including a reciprocating needle, a loop-taker, a thread-case mounted in said loop-taker and around which said loop-taker is adapted to cast a loop of needle-thread, a stop-element for limiting rotation of said thread-case in opposite directions upon its own axis, and means for moving said thread-case axis laterally to provide a 45 free passage for the needle-thread loop past opposite sides of said stop-element.

3. In a sewing machine, a stitch-forming mechanism including a reciprocating needle, a loop-taker, a thread-case mounted in said loop-taker and around which said loop-taker is adapted to cast a loop of needle-thread, a stop-element for limiting rotation of said thread-case upon its own axis, means for moving said thread-case axis laterally, and means rendered active by the lat-

eral movements of said axis to oscillate the thread-case in a direction opposite to the direction of movement of said loop-taker and provide a free passage for the needle-thread loop past said stop-element.

4. In a sewing machine, a stitch-forming mechanism including a reciprocating needle, a loop-taker, a thread-case mounted in said loop-taker and around which said loop-taker is adapted to cast a loop of needle-thread, a stop-element for limiting the rotation of said thread-case upon its own axis, a cam-element upon said thread-case, a coacting cam-surface, and means for moving said thread-case axis laterally to render 70 said cam-element and cam-surface active to oscillate the thread-case and thereby provide a free passage for the needle-thread loop past said stop-element.

5. In a sewing machine, a stitch-forming 80 mechanism including a reciprocating needle, a rotary loop-taker, a thread-case mounted in said loop-taker and eccentrically to the axis of rotation of the latter, a stop-element for limiting rotation of said 85 thread-case upon its own axis, and means including the eccentric mounting of the thread-case in said loop-taker for providing a free passage past said stop-element for a loop of needle-thread cast around the 90 thread-case by said loop-taker.

6. In a sewing machine, a stitch-forming mechanism including a reciprocating needle, a loop-taker having an eccentric raceway, a thread-case provided with a peripheral bearing rib journaled in said raceway, a stop-element for limiting rotation of said 95 thread-case upon its own axis, a cam-element upon said thread-case, and a stationary cam-surface adapted to coact with said cam-element to oscillate the thread-case and provide a free passage for a loop of needle-thread past said stop-element.

7. In a sewing machine, a stitch-forming mechanism including a reciprocating needle, a rotary loop-taker having an eccentric raceway, a thread-case provided with a peripheral bearing rib journaled in said raceway, a stop-lug upon said thread-case, a threat-plate provided with a notch adapted to be entered by said stop-lug for limiting rotation of said thread-case upon its own axis, a cam-element upon said thread-case and a stationary cam-surface adapted to coact with said cam-element to provide a 105 free passage for a loop of needle-thread past said stop-element.

In testimony whereof I have signed my name to this specification.

RALPH PETTI.
